UNITED STATES PATENT OFFICE.

CHARLES A. HUSSEY, OF NEW YORK, N. Y.

CASE FOR SECONDARY ELECTRIC CLOCKS.

SPECIFICATION forming part of Letters Patent No. 350,435, dated October 5, 1886.

Application filed July 1, 1886. Serial No. 206,777. (No model.)

To all whom it may concern:

Be it known that I, CHARLES A. HUSSEY, of New York, in the county and State of New York, have invented a certain new and useful 5 Improvement in Electric Clocks, of which the following is a specification.

My improvement particularly relates to clocks in which time is caused to be indicated by electricity, and applies particularly to the 10 cases in which such clocks are contained.

I will describe in detail an electric clock embodying my improvement, and then point out the novel features in a claim.

In the accompanying drawings, Figure 1 is 15 an electric clock embodying my improvement, the case being open. Fig. 2 is a perspective view thereof, the case being closed and a portion thereof being broken away to disclose certain parts.

20 Similar letters of reference designate corresponding parts in both figures.

A' designate two portions of a clock-case, which are hinged together, as at a. Each of the portions is hollow. The portion A 25 constitutes the front of the case and the portion A' the back thereof. The portion A is provided upon its front side with a dial, a'. The dial-plate is rigidly affixed to the case.

B designate electrical apparatus adapted to 30 be operated periodically to indicate time upon the dial a'. As shown, said apparatus is secured to a plate, b, which in turn is rigidly affixed to the rear side of the dial-plate. It is therefore apparent that when the portion A 35 of the case is raised up the apparatus B will be carried with it, and access may be readily had to said apparatus, if desirable. By utilizing the dial-plate as a support for the apparatus B the necessity for any independent support for the said apparatus is avoided.

40 The apparatus B consists, essentially, of a train of time-wheels, b², actuated from an electro-magnet, b³.

C designates circuit-wires extending between the electro-magnet b³ and contact-pieces D, 45 mounted, as shown, upon a wooden block, d, secured to the plate b. The portion A' of the case has a closed back, and is of sufficient depth to admit of the portions A A' being closed without the apparatus B coming in contact with the back of the portion A'.

J designates contact-pieces affixed to the back of the portion A', inside the latter. Circuit-wires j extend from said contact-pieces to binding-posts j', located outside the case. 55 When the portions A A' are closed together, the contact-pieces D and J will be brought into contact, and an electrical circuit will thus be established, as shown more clearly in Fig. 2. The two portions may be secured together 60 when closed by a catch, E.

It will be seen that by my improvement I avoid the necessity for removing the back of the case, or the hands and dial-plate, when it is desired to reach the time mechanism, whereby 65 a considerable saving in time and labor is effected.

What I claim as my invention, and desire to secure by Letters Patent, is—

In an electric clock, the combination, with 70 time mechanism, of a case composed of two portions hinged together, a time-dial secured in one of said portions and having said time mechanism secured to it, contact-pieces in said portion, also supported by the dial, contact-pieces in the other portion of the case so arranged that when said case is closed the contact-pieces will be brought together, and conducting-wires, substantially as specified. 75

C. A. HUSSEY.
